UNITED STATES PATENT OFFICE.

EDWARD N. GREENLEAF AND GEORGE T. HANSEN, OF SALT LAKE CITY, UTAH,
ASSIGNORS TO ALLIS-CHALMERS MANUFACTURING COMPANY, OF MILWAU-
KEE, WISCONSIN, A CORPORATION OF DELAWARE.

GRANULATOR.

1,309,800.

Specification of Letters Patent. Patented July 15, 1919.

Application filed August 19, 1915. Serial No. 46,723.

To all whom it may concern:

Be it known that we, EDWARD N. GREENLEAF and GEORGE T. HANSEN, citizens of the United States, residing at Salt Lake City, 5 in the county of Salt Lake and State of Utah, have invented a certain new and useful Improvement in Granulators, of which the following is a specification.

This invention relates to improvements in 10 the construction of granulators of the type commonly employed in the reduction of rock, ore, coal and similar substances.

An object of the invention is to provide 15 a granulator which is simple in construction and efficient in operation. Another object is to provide simple and efficient means for varying the pulp level within a granulator. A further object is to provide means for 20 varying the pulp level without affecting the screening area of the discharge. Still another object is to produce a simple and compact device for fixing both the size of the product discharged and the head or level of the material at the discharge end of the mill. 25 Another object is to provide a discharge screen which is self cleaning.

It has been found, especially in the operation of wet grinding tube and ball mills used 30 for the reduction of ores, that for certain conditions of operation, such as the kind of material treated, the ratio of reduction, the size of discharged product desired and others, a predetermined level of pulp within the mill is more efficient and desirable than 35 any other. This desirable pulp level is ordinarily somewhere between the periphery and the central axis of the mill. By operating a wet grinding mill with the pulp level at or near the central axis, it is in most cases im- 40 possible to obtain the maximum ratio and rate of reduction, and also to produce a uniform product at the discharge. In an endeavor to provide means for maintaining the most efficient and desirable pulp level 45 in mills of this type, several so-called quick discharge wet grinding ball mills have been developed. An objection to these mills has been the fact that they were not provided with suitable means which were unaffected 50 by feed variations, for positively adjusting the pulp level within the mill. In these prior quick discharge mills it has happened that owing to undesirable and uncontrollable excessive variations in the rate of feed,

the pulp level would be reduced to such an 55 extent that the cushion for the grinding and crushing bodies afforded by the pulp, would be entirely eliminated and the crushing bodies would violently impinge upon each other and upon the mill linings, thus prac- 60 tically ruining the mill in a short time.

With the present invention the pulp level necessary to produce the most efficient grinding and a uniform rate of discharge is 65 readily established and maintained without permitting undue wear on the grinding elements. The device of the present invention permits establishment of a pulp level which is the most efficient and desirable for any 70 condition of operation and which will not vary in accordance with variations in the rate of feed. The mill of the present invention may be readily adapted to any ratio of crushing within certain limits, either when operated as a tube mill or a ball mill 75 and either for wet or dry grinding. By the present invention destruction of the charge of grinding bodies and of the mill liners, due to complete or nearly complete failure of the feed and of resulting loss of 80 the necessary cushioning pulp level, is also avoided.

A clear conception of an embodiment of the invention may be had by referring to the drawing accompanying and forming a part 85 of this specification in which like reference characters designate the same or similar parts in the various views.

Figure 1 is a fragmentary longitudinal section through a wet grinding ball mill, 90 showing the discharge end thereof.

Fig. 2 is a transverse vertical section through a wet grinding ball mill, a portion of some of the elements being broken away, and the section being taken along the line 95 II-II of Fig. 1 looking in the direction of the arrow.

While the invention is disclosed as specifically applied to a wet grinding ball mill, the grinding balls being of the ordinary 100 type and therefore omitted from the disclosure, it should be understood that the invention is applicable to other similar types of granulators.

The portion of the mill disclosed in the 105 drawing comprises a casing made up a shell 1 and an end head 2. A vertical partition which divides the interior of the casing into

a grinding chamber 14 and a discharge chamber 15, is mounted within the shell 1. The end head 2 has a trunnion 3 formed integral therewith and located concentrically of the shell 1. The trunnion 3 is rotatably supported in a bearing 4 mounted upon a pedestal, these elements being of usual construction. The shell 1 is provided with removable sectional shell liners 5, of any suitable formation, while the trunnion 3 and end head 2 are provided with protecting liners 6, 16, respectively.

The partition which divides the mill casting into the grinding and discharge chambers 14, 15, comprises essentially a series of segments each consisting of a nest of radial screen bars 7, and a perforated sectional wall 9. The wall 9 is spaced from the screen bars 7 and is located on the discharge side of the partition. The holes or perforations 10 formed in the wall 9 are of sufficient size so that only a small portion of the total number is necessary to permit free passage of the reduced material from the grinding to the discharge chamber of the mill. Plugs 17 which may be made of wood or any other suitable material, are disclosed as having been inserted in the two outer circular rows of perforations 10, and maintain the level of the pulp 18 in the grinding chamber 14 at the point indicated in Fig. 1.

Formed directly upon the end head liner 16 and abutting the perforated wall 9, is a series of lifting vanes or ribs 11. The removable bolts 13 clamp the wall 9 directly against the ribs 11, serving also to retain the peripheral portions of the liners 16 in place against the end head 2. The retaining plate 8 engages the inner ends of the screen segments, this plate 8 together with the screen bars 7 and the inner edges of the segments of the wall 9 and liner 16 being held in place by means of removable bolts 12.

During the normal operation of the mill, the shell 1 and end head 2 are rotated, causing the grinding bodies within the chamber 14 to be lifted upwardly by the advancing mill liners, and to successively cascade over the upper surface of the charge. The material which is to be ground together with the liquid in a wet grinding mill, is admitted to the chamber 14 at the feed end of the mill. As the material passes through the chamber 14, it is reduced to the desired fineness by the action of the grinding elements, and is thoroughly mixed with the liquid to form a pulp.

As the material is sufficiently reduced to pass through the spaces between the screen bars 7, it is carried forward by the liquid and through the screen spaces. The portion of the reduced material which is in suspension with the liquid at the surface of the pulp passing through the screen, is carried

through the outer set of unobstructed openings 10 and into the path of the advancing ribs 11. The ribs 11, due to the rotation of the mill, advance and elevate the material thus discharged, eventually permitting the same to flow out of the mill through the trunnion 3.

As the grinding bodies during rotation of the mill, cascade down the charge and strike the pulp 18, they agitate this pulp and produce waves the action of which is to produce a back and forth motion of the thin pulp between the screen bars 7, thus tending to prevent material from lodging between the bars. The radial disposition of the bars 7 together with the free space formed on both sides of the bars 7, enhances this cleaning action and produces a screen which is self cleaning. As the relatively heavy freely tumbling comminuting bodies impinge against and roll over the substantially radial screen bars 7, these bars are vibrated, thus further augmenting the automatic cleansing of the screen.

It will be noted, that by inserting any desirable number of plugs 17 in openings 10, the level of the pulp 18 may be maintained at the most efficient and desirable point. If it is found during operation of the mill, that the product discharged from the mill is not as desired either in quantity or quality, the pulp level may be varied to produce the desired results. The nests of screen bars 7 may be readily removed by removal of the adjacent liners 5 and plate 8, after which the plugs 17 may be readily manipulated. The screen bars 7 are removed independently of the wall 9, thus permitting variation of the pulp level without disturbing the perforated wall.

The insertion of the plugs 17 positively fixes the pulp level, and complete removal of the pulp from within the mill is impossible. The plugs 17 are prevented from being dislodged by the screen bars 7 which prevent such dislodgment.

It should be understood that it is not desired to be limited to the exact details of construction shown and described, for obvious modifications will occur to a person skilled in the art.

It is claimed and desired to secure by Letters Patent,—

1. In combination, a casing forming a comminuting chamber, a discharge sizing screen comprising spaced bars located directly adjacent an end of said chamber, and means within said casing for gaging the level of liquid in said chamber, said means being spaced from and located on the side of said screen remote from said chamber.

2. In combination, a casing forming a comminuting chamber, a discharge sizing screen comprising nests of substantially radial bars located directly adjacent an end of

said chamber, and means within said casing for gaging the level of liquid in said chamber, said means being spaced from and located on the side of said screen remote from 5 said chamber.

3. In combination, a casing forming a comminuting chamber, a discharge sizing screen comprising spaced bars located directly adjacent an end of said chamber, a 10 perforated wall within said casing, and means for closing some of the perforations of said wall to gage the level of liquid in said chamber, said wall being spaced from and located on the side of said screen remote 15 from said chamber.

4. In combination, a casing forming a comminuting chamber, a discharge sizing screen comprising nests of substantially radial bars located directly adjacent an end 20 of said chamber, a perforated wall within said casing, and means for closing some of the perforations of said wall to gage the level of liquid in said chamber, said wall being spaced from and located on the side of 25 said screen remote from said chamber.

5. In combination, a casing forming a comminuting chamber, a discharge sizing

screen comprising spaced bars located directly adjacent an end of said chamber, a perforated wall within said casing, and a 30 plurality of plugs for closing some of the perforations of said wall to gage the level of liquid in said chamber, said wall being spaced from and located on the side of said screen remote from said chamber, and said 35 screen serving to prevent displacement of said plugs.

6. In combination, a casing forming a comminuting chamber, a discharge sizing screen comprising nests of substantially radial bars located directly adjacent an end of said chamber, a perforated wall within said casing, and a plurality of plugs for closing 40 some of the perforations of said wall to gage the level of liquid in said chamber, 45 said wall being spaced from and located on the side of said screen remote from said chamber, and said screen serving to prevent displacement of said plugs.

In testimony whereof, the signatures of 50 the inventors are affixed hereto.

EDWARD N. GREENLEAF.
GEORGE T. HANSEN.
